UNITED STATES PATENT OFFICE.

LEE E. ABBE, OF SALEM, OREGON.

SAFETY MILK-BOTTLE RETAINER.

Application filed January 28, 1925. Serial No. 5,222.

This invention relates to devices for safe-guarding bottles of milk from theft or contamination after delivery to the customer.

The primary object of my invention is the provision of a receptacle for milk bottles in which the bottles may be deposited by the delivery man within the retainer without trouble or delay and which retains the bottle in a safe and protected manner 10 wherein the bottle itself serves to prevent the opening of the retainer except by one having a key thereto.

Other objects and advantages relating to details of construction and arrangement of parts will be readily apparent in the course 15 of the detailed description to follow.

The accompanying drawings illustrate by way of example one form in which my invention may be embodied, in which:

20 Figure 1 is a perspective view of a milk bottle retainer embodying my invention shown in closed condition.

Fig. 2 is a vertical cross sectional view on the line 2—2 of Fig. 3, and showing a 25 pint milk-bottle therein to illustrate the action of the means provided to guard against unauthorized opening of the case.

Fig. 3 is a view in vertical cross section on line 3—3 of Fig. 2.

30 Fig. 4 is a top plan view of Fig. 2 with the upper slide-cover removed, and with parts being broken away to disclose construction.

Fig. 5 is a view in horizontal cross section on line 5—5 of Fig. 2, showing the drawer 35 pulled out in placing a bottle in the retainer.

Fig. 6 is a perspective view of one of the guard-plates detached.

Referring to said views, the reference numerals 1 and 2 indicate the opposite side walls of the casing of my improved milk-bottle retainer, and 3 and 4 the rear and front walls thereof, respectively. Said casing is formed of sheet metal in rectangular configuration and its side walls 1 and 2 are 40 formed at their upper edges with corresponding horizontal, inturned flanges 5. The upper edge of the rear wall 3 is similarly flanged inwardly, as at 6, at a lower elevation than the flanges 5. The front wall 45 terminates at a distance below the flanges 5 to afford an entrance slot 7 for a slide-cover 8 to open and close the upper end of the retainer. When closed the slide-cover rests at the rear upon the flange 6 and under the flanges 5. The forward edge of the cover is turned downwardly, as at 9, and

may be formed with a slot 10 through which a staple 10' rigidly mounted in the front wall may extend. A padlock 11 is utilized to lock the cover in closed position in a 60 well understood manner.

The bottom of the retainer case is provided with a transverse strip 12 adjacent the front wall 4 and may be integral with one of the side walls. The major portion of said bottom is left open for the entrance of the milk-bottle 13 except for the flanges 14 projecting inwardly from the side and rear walls upon which and said strip a drawer 15 is adapted to slide. The front wall 4 terminates short 70 of the strip 12 to provide an opening 16 across the front of the casing to admit the entrance of said drawer. The drawer 15 is formed with a plane bottom 17 and marginal walls 18 extending upwardly for approximately one-half an inch to slide freely through the opening 16. The front wall 19 of the drawer may be of somewhat greater width so that its upper edge will engage the lower outer face of the front wall 4 of the 80 case. A lug 20 extends outwardly from the front wall 17 through which the drawer may be manipulated.

A shallow U-shaped frame 21 is rigidly attached to the front wall of the case and has a bar 22 at each side in close proximity to the side walls 1 and 2. Said bars extend upwardly to the plane of the upper edge of the front wall 4 and of the flange 6 to provide additional tracks upon which the 90 slide-cover 8 may be supported. Adjacent the lower edges of the bars 22 lugs 23 are integrally formed to provide a rest for a series of guard-plates 24, 25 and 26. Said plates are each provided with pivotal pins 95 27 extending laterally from the fore edges thereof and which are mounted for swinging movements in the bars 22. Said plates are arranged in superposed relation and are arranged in the frame to have their rear edges extend toward the rear wall 3 in progressively closer relation from the lowest to the highest plate. The lowermost plate 24 rests upon the lugs 23 with the next plate 25 supported thereby while the upper plate 26 rests upon the plate 25 when in inoperative position.

Said guard-plates extend toward the rear wall of the case to progressively greater distances from the lower plate 24 of the top-most plate 26, as has been stated, the purpose being to admit sufficient space between the 110

rear, free edge of the respective plate and the rear wall 3 to receive a standard milk-bottle of quart, pint and half-pint sizes, respectively, therebetween to prevent the bottle being shifted in the retainer for the purpose of unauthorized removal, as will be more fully explained.

The operation of my bottle retaining devices may be described as follows: With the 10 slide-cover closed and locked as indicated in Fig. 1 and the case empty, the deliverer of the milk will first pull out the drawer 15, as shown in Fig. 5, to an extent that will allow him to push a bottle of milk or cream upwardly through the opening thus made in the bottom of the case. He holds the bottle pushed up in the case with the fingers of one hand so that it is above the drawer and then pushes back the drawer into the 15 case while allowing the bottle to slip down onto the drawer as he withdraws his hand and to be supported thereby, as plainly indicated in Fig. 2.

In placing the bottle as described a half-pint bottle will not displace any of the plates but will substantially fill up the space between the furtherest projecting plate 26 and the rear wall 3. In the case of a pint bottle the plate 26 will be displaced and shoved 20 upwardly by the bottle, as seen in Fig. 2, while a quart bottle will tilt upwardly both plates 25 and 26 and lie between the smallest plate 24 and the rear wall.

When positioned as described the bottles 25 cannot be removed from the retainer in a clandestine manner for if it is attempted to pull the drawer out to reach within the casing, the rear wall 18 of the drawer will be blocked by the bottle itself which cannot 30 move with the drawer owing to the respective plate 24, 25 or 26 blocking the way. To remove the bottle the slide-cover 8 must be unlocked and the bottle removed from the 35 opened top which, upon the removal of the bottle, automatically replaces the retainer in condition to receive a new bottle.

Although I have described my invention with considerable detail I wish it to be understood that I do not confine myself to the 40 precise construction shown as it is deemed that various changes in details of construction and modification of arrangement may be made in the invention within the scope of the claims without departing from the 45 spirit of the invention. For example, the casing may be constructed to provide for the reception of a plurality of bottles by

duplication of the described apparatus within a single casing having rigid vertical partitions between the several bottle-holding compartments.

Having described my invention, what I claim as new, is:—

1. A milk-bottle retainer, consisting of a 65 casing, an openable cover at the upper end of said casing, means to lock said cover, and a slidable drawer forming the bottom of said casing and providing an entrance when open into the casing, said drawer having a 70 bottle-engaging wall at its rear end.

2. A milk-bottle retainer, consisting of a 75 casing, an openable cover at the upper end of the casing, means to lock the cover, a slidable drawer forming the bottom of said casing and providing an entrance into the 80 casing when withdrawn, said drawer having a bottle-engaging wall at its rear end, and means engageable with the front of the bottle to prevent forward movement thereof.

3. A milk-bottle retainer, comprising a 85 casing having a lockable cover, a bottom drawer slidable in the casing and affording an opening in the bottom of the casing when said drawer is withdrawn, means provided on said drawer to engage a bottle seated upon the 90 drawer, and means adaptable to the various sizes of bottles to hold them adjacent the rear wall of the casing.

4. A milk-bottle retainer, comprising a 95 casing having a cover, a bottom drawer slid- 100 able in the casing and affording an opening in the bottom of the casing when said drawer is withdrawn, means provided on the drawer to engage a bottle seated upon the drawer, and a plurality of plates pivotally connected adjacent the front wall of the casing and extending in horizontal directions to engage the bottle placed upon said drawer.

5. A milk-bottle retainer, comprising a 105 casing having a cover, a bottom drawer slid- 110 able in the casing and affording an opening in the bottom of the casing when said drawer is withdrawn, means provided on the drawer to engage a bottle seated upon the drawer, and a plurality of superposed plates pivotally mounted adjacent the front wall of the casing, the overlying plates, respectively, extending further toward the rear wall of the casing than the one im- mediately therebelow.

LEE E. ABBE.
